UNITED STATES PATENT OFFICE.

WICKLIFF B. MITCHELL, OF OWENSBURG, INDIANA.

DESIGN FOR A DOOR-STOP.

SPECIFICATION forming part of Design No. 35,155, dated October 1, 1901.

Application filed August 23, 1901. Serial No. 73,103. Term of patent 7 years.

To all whom it may concern:

Be it known that I, WICKLIFF B. MITCHELL, a citizen of the United States, residing at Owensburg, in the county of Greene and State of Indiana, have invented and produced a new and original Design for a Door-Stop, of which the following is a specification.

This invention relates to a new and original design for a door-stop, and the essential features reside in the design as illustrated in the accompanying drawings, wherein—

Figure 1 is a perspective view of a door-stop embodying the design. Fig. 2 is an edge elevation of the same.

15 The design is characterized by an approximately circular body 1, mainly in the form of a rim having the terminals 2 inturned within the plane of the body and curved outwardly in reverse directions. The terminals 2 connect with a circular securing-plate 3, having

a central circular boss 4, with an opening 5 therethrough and through the said plate 3. Extending from the upper portion of the plate 3 is a member 6, which merges into the upper central part of the body 1 by curved side edges 25 7. From the center of the upper portion of the body 1 a projection 8 extends forwardly, and the edge of the body is formed with grooves 9.

Having thus described the invention, what 30 is claimed as new is—

The design for a door-stop, as herein shown and described.

In testimony that I claim the foregoing as my own I have hereto affixed my signature in 35 the presence of two witnesses.

WICKLIFF B. MITCHELL.
